UNITED STATES PATENT OFFICE.

MAX SHERMAN, OF BROOKLYN, NEW YORK.

DESIGN FOR A BEVERAGE DISPENSER.

Application filed February 12, 1924. Serial No. 8,618. Term of patent 3½ years.

To all whom it may concern:

Be it known that I, MAX SHERMAN, a citizen of the United States, residing at Brooklyn, in the county of Kings and State of New York, have invented a new, original, and ornamental Design for a Beverage Dispenser, of which the following is a specification, reference being had to the accompanying drawing, forming part thereof.

Fig. 1 is a front view of the ornamental design for a beverage dispenser of the present invention.

Fig. 2 is a side view of the same.

I claim:

The ornamental design for a beverage dispenser as shown.

In witness whereof, I have hereunto set my name this 9th day of Feb., 1924.

MAX SHERMAN.
